UNITED STATES PATENT OFFICE

MORRIS GREEN, OF SCRANTON, PENNSYLVANIA

DESIGN FOR A SHRINE

Application filed April 7, 1933. Serial No. 47,722. Term of patent 7 years.

To all whom it may concern:

Be it known that I, MORRIS GREEN, a citizen of Poland, and having taken out his first naturalization papers for citizenship in the U. S. A., residing at Scranton, in the county of Lackawanna and State of Pennsylvania, have invented a new, original, and ornamental Design for a Shrine, as shown in the accompanying drawing and described in the following specification.

In the accompanying drawing:

I claim:
The ornamental design for a shrine as shown.

MORRIS GREEN.
